[57] CLAIM

The ornamental design for clothes hanger organizer, as shown and described.

DESCRIPTION

FIG. 1 is a front view of a clothes hanger organizer showing my new design, the rear view being a mirror image;

FIG. 2 is a side view thereof, the side opposite being identical except for the hook;

FIG. 3 is a perspective view thereof;

FIG. 4 is a front view of a modified embodiment of the design shown in FIGS. 1-3, the rear view being a mirror image;

FIG. 5 is a side view thereof, the side opposite being identical except for the hook; and,

FIG. 6 is a perspective view thereof.
